CALCULATING MACHINE

Harvie J. Duke, Orange, N. J., assignor to Gardner Company, Orange, N. J., a corporation of Delaware

Refiled for abandoned application Serial No. 614,195, May 28, 1932. This application December 14, 1934, Serial No. 757,496

1 Claim. (Cl. 235—60)

The invention has relation to calculating machines, and more particularly to means for controlling the release of the preset digit keys of such a machine at the end of an operation. The 5 present application is a substitute for application Serial No. 614,195, filed May 28, 1932, which became abandoned on May 3, 1933.

It is common to provide motor operated calculating machines with an operation key, which may be depressed and held depressed until the machine has operated for the desired number of cycles, to add or subtract the amount set in the keyboard a given number of times to or from the amount set in the accumulator. Upon manual release of such key, the machine will complete the cycle in which it is operating, and the registering mechanism will thereupon be brought to rest. The present invention contemplates a digit key release mechanism which will operate in a 20 similar manner and will be controlled from the above described registering operation key.

The invention consists in the novel construction and combination of parts, as set forth in the appended claim.

25 In the accompanying drawings, illustrating the invention:

Fig. 1 is a longitudinal section through a calculating machine embodying the invention, showing the keyboard and registering mechanism 30 thereof.

Fig. 2 is a similar view, showing the registration and key release control mechanism.

Fig. 3 is a similar view showing a modified operation key arrangement.

35 Fig. 4 is a detail side view of the locking plate and associated parts.

Fig. 5 is a detail side view of the key release and non-release mechanism.

These drawings illustrate a machine of the 40 Gardner type such as that disclosed in British Patent #293,080, and equipped with motor operating means, as disclosed in U. S. Patent No. 1,932,013, October 24, 1933, to Loring P. Crosman.

45 Amounts to be registered in this machine are set up on the digit keys 215 (Fig. 1) which keys are latched in active depressed position by sliding locking plates 213. The registering mechanism is thereupon operated by imparting one or more reciprocations to shaft 301, said shaft being provided with a frame 318 movable to allow operation of a series of three-armed levers 610, under the influence of springs 683. The upper arms of levers 610 are connected to a series of stop bars 615, having lugs adapted to contact 50 55 with the depressed keys, in well known manner,

to limit the movement of the levers 610 in accordance with the amounts set up. The forward arms of levers 610 are provided with toothed segments engaging the pinions 472 of one or more accumulators. The rearward arms of levers 610 carry type bars 611 which are adapted to bring type to the printing line in accordance with the amounts set on the keyboard, suitable printing mechanism being provided for printing such amounts during the movement of shaft 301.

5 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

The digit keys 215 which are latched in depressed position by the engagement of suitable 40

teeth on the slides 213 with notches in the key stems, are released from the latching slides 213 by means of levers 214 (Fig. 1) fulcrumed at 204 below the keyboard plate and having arms engaging suitable projections of the slides 213. The 45 levers 214 are operated by a bail 227 pivoted at 252 (Figs. 2, 4, 5) in the framing of the machine.

Releasing bail 227 may be operated at any time by a correction key 272, the stem of said key engaging a pin 256 in the end plate of said bail. 50 Means are also provided for moving the releasing bail 227 automatically during the last portion of a cycle of registering movement, said means comprising lever 327, connected by rod 321 with arm 316, the free end of lever 327 engaging a stud 55

222 connected with a rocker 220, pivoted at 262 on the framing of the machine. Rocker 220 carries a pivoted hook 221, normally held by a suitable spring in position to engage a pin 263 in the 5 end plate of bail 227. In the forward reciprocation of shaft 301, lever 327 will pass idly beyond pin 222, which is yieldably mounted on rocker 220, and upon the rearward reciprocation of shaft 301 lever 327, contacting pin 222, will move rocker 10 220 and, through hook 221 and pin 263 will move the releasing bail 227 to release the depressed keys.

The key which according to the present invention controls the registering and the key release mechanism may be associated with other keys controlling one or the other of said mechanisms, in various combinations. One such combination is illustrated in Fig. 2, wherein a registration and key release control key 142 is provided, said key being so arranged that other registration controlling keys, for instance, keys controlling plus and minus operation respectively, may operate, through latch 112, without controlling the key release mechanism. Key 142 controls 20 the key release mechanism as follows: A cam 143 on key 142 is adapted to contact with a stud on a slide plate 145, the other end of said plate having a tooth 151 (Figs. 4 and 5) engaging hook 221. As key 142 is depressed plate 145 will be 30 shifted, and tooth 151 will rock the hook 221 and hold the same out of engaging position with pin 263 of the key releasing bail 227. Therefore, so long as this key is held depressed, the operation 35 of lever 327 at the end of the cycle will be idle with respect to bail 227, and the digit keys 215 will remain depressed. Upon release of key 142, hook 221 will be pulled by its spring back into engaging position, so that the digit keys will be released upon the completion of the registration then being effected.

Key 142 controls latch 112 by means of the cam 143 and slide 145, the latter, engaging the upper end of a lever 144, which lever has operative contact with a lug of latch 112. Thus, so long as key 45 142 is held depressed latch 112 will be held out of engagement, and clutch lever 106 will not contact with clutch pawl 141 to disengage the clutch.

An interlock is shown between key 142 and certain other operating keys of the machine. The 50 keys illustrated comprise a sub-total key 273 and total key 278, of well known construction. A locking plate 146 (Fig. 4) has a lug engaging lever 144, and near its other end is provided with a second lug 147, adapted when the lever 144 is 55 moved to operative position to lie in the path of

the ends of key levers 273 and 278. A spring 152 returns locking plate 146 to normal position upon release of key 142. In the normal position of plate 146, depression of key 273 or key 278 will bring the end of the respective key lever in front of lug 147, whereupon plate 146 will hold lever 144 and key 142 against operation.

Another combination of keys is illustrated in Fig. 3, wherein a plurality of operation keys, such as the usual plus and minus keys 114 and 214, 10 will control the key release mechanism as well as the registering mechanism, and wherein a non-release key 276 may be provided, said key having a notch which may be engaged with the keyboard plate to hold the parts in non-key releasing position, so that no automatic clearing of the keyboard will occur.

The plus key 114 engages the end of a lever 113, similar to the lever 144, the minus key 274 operating lever 113 through an interposed lever 117. The locking plate 146 (illustrated in Fig. 4) has a lug engaging the end of lever 113, whereby the plate is operated as above described. Plate 146 is also provided with a stud 149 engaging slide 145. Thus, upon operation of key 114 or key 274 lever 113 and plate 146 will move slide 145 and bring the tooth of said slide against hook 221, to move the hook out of engaging relation with pin 263, in which position the hook will be held so long as the depression of key 114 or key 274 holds the 30 lever 113 in operating position. The lever 113 also operates latch 112 in the manner above described.

It may be noted that Figs. 4 and 5 illustrate mechanism common to both forms of the invention, except that pin 149, shown in Fig. 4 is omitted from the embodiment illustrated in Fig. 2.

I claim:

In a calculating machine having a motor, cyclic operating means, driving connections between 40 said motor and said operating means, digit setting keys controlling entry of items, and key locks therefor; the combination with cyclically operated means for breaking the driving connections and bringing the registering means to rest, 45 of cyclically operated means for releasing said key locks, timed for substantially simultaneous action with the connection breaking means, and a freely retractable device including an operation key disabling in manually set position said 50 connection breaking means and said lock releasing means, the breaking means and the releasing means being adapted to operate following manual release of said key.

HARVIE J. DUKE. 55
